UNITED STATES PATENT OFFICE.

JAMES H. FULLER, OF COLUMBUS, OHIO.

MEANS FOR AIDING THE SORTING OF DOCUMENTS.

Application filed November 23, 1925. Serial No. 71,026.

The object of the invention is a means or apparatus for facilitating the classification or sorting of documents, such, for example, as salesmen's reports, letters, shop records and so forth that come in uniform width or length. To illustrate, in the tobacco and cigar business as conducted by one or more large concerns in the United States, the country is divided geographically into departments and divisions and districts or "assignments" of divisions, the departments having supervisors and the divisions managers under whose direction are salesmen, the latter being assigned to particular districts in which they make daily visits to retail dealers to take orders for the goods needed. These salesmen are required to make daily reports of their sales upon a form sheet of uniform dimensions printed in connection with spaces to be filled in by them giving in detail the information required. These reports are sent by mail into the department manager who arranges them or through a clerk causes them to be arranged each week for convenient future reference in alphabetical order as respects the names of the salesmen and also if desired in chronological order.

In the illustration instanced the sorting is not done each day nor even at the end of the week but during each week in respect of the next preceding week so as to include in the sorting those reports that arrive late by reason of the time consumed in mail transportation, it being evident that a Saturday's report will not ordinarily arrive until Monday or later. Where a department is large or populous and the salesmen numerous the sorting of the reports, unless some mechanical aid be provided requires much handling and rehandling and shifting about of the documents to get them into the proper order so that they can be quickly located and referred to at some later time. My invention will be useful in many businesses other than that herein specifically instanced.

The invention is embodied in the example herein shown and described, the features of novelty being finally claimed.

50 In the accompanying drawing—

Figure 1 is a top plan view of an apparatus according to the invention.

Fig. 2 is a front view of the left hand side of the same, both sides being alike.

55 Fig. 3 is a view in elevation looking at the

left hand end of the device with the near leg removed.

Fig. 4 is a detail view of a ticket or slip of paper designed to bear the name of a salesman or division manager.

Fig. 5 shows a section of the ribbon employed with a ticket like that shown in Fig. 4 inserted.

In the views A designates an elongated rectangular table supported by legs B upon which table the documents to be sorted are laid as hereinafter explained. The table is provided with a pair of longitudinal finger grooves A'. The rear of the table is provided with a permanent rail C over which ribbons D and P are shifted. At each end of the table is journaled a spool E to which are connected the ends of the ribbon D. The ribbon D has stitched to it by transverse stitches and in regularly occurring units of measurement as hereinafter described at opposite margins narrow strips D' to provide opposed pocket-like openings to receive the tapered ends of flexible paper tickets F (see Fig. 4) bearing the names of the division manager and the salesmen under his direction and also, as shown, a series of numbers. These tickets are made removable so as to permit of substitution and transposition where new managers or salesmen take the places of those old, resigned, deceased or discharged. The names of the salesmen are arranged on the ribbon in alphabetical sequence following the distinctively marked ticket bearing the name of the division manager. The spools E are turned by suitable crank shafts J fixed on which are gears K engaging pinions L fixed on the spools to cause rapid winding of the ribbon in one direction or the other so as to present in the exposed portion of the ribbon the particular set of names desired or the series of numbers. The ribbon can be held from slipping out of its adjusted position by means of screws M clamping on the shaft 100 the parts of the crank shaft bearing.

The rail in front of said movable ribbon is provided with a stationary marking or scale N of equally spaced lines dividing the rail into divisions equalling those of the ribbon D containing the name tickets and equal to a unit of measurement of the width or length of the document to be sorted, as, for example, one inch. The spaces of the permanent scale are numbered from left to 110

right with numerals in arithmetical series, for example, from 1 to 35.

Connected with additional spools O is another ribbon P bearing transverse dividing lines forming spaces equaling those of the permanent scale. This ribbon is also provided with an arithmetical series of numbers—one for each division—commencing at the left hand end as shown. This ribbon is adjustable to the right or left by providing the shafts of the spools with knurled heads that can be turned with the fingers of the user. Stops O' can be provided to prevent the ribbon P from running off the rail.

It will therefore be observed that the ribbon D can be moved to have the middles of its divisions and the names thereon coincide with the lines of the permanent scale. It will also be observed that the movable ribbon P can be moved to have its lines of division coincide with any of the lines of division of the permanent scale and the coincidence commence with any digit or number of the permanent scale. The ribbon P can, of course, be similarly adjusted with respect to the numbered portion of the ribbon D if desired. The point at which the coincidence of the ribbon P with the permanent scale is determined, in practice, by the width or length of the documents to be sorted. For example, if the width of the document to be sorted is eight inches the ribbon P will be adjusted to have its division line 1 coincide with the division line 9 of the permanent scale and the name on ribbon D will be adjusted to have the alphabetically first name coincide with the first division of the permanent scale.

Supported in guides Q secured on the lower side of the table is a slide R having stops like that at S to abut against a cross bar T to limit the extent of withdrawal of the slide. Said slide when drawn out affords a convenient place to initially receive the pile of documents to be sorted.

In practice the reports of the various salesmen are laid on the table each with its upper left hand corner coinciding with the line opposite which is his name on the ribbon D. All the reports for the week are laid in the same manner so that there will result a layer of reports some projecting more and some less to the right than the others and, of course, according to the position determined by the alphabetical position of the name of the salesman but all the reports of a particular salesman will lie in the same relative position vertically to the table and the scale, or to particularize, all the reports of the salesman whose family name begins with the lowest letter of the alphabet in the group will project equally beyond the reports of the salesman having the next lowest letter. By taking at the grooves A' with the fingers of the right

hand the margins of those reports that project to the right beyond all the other reports and pressing down and holding the other nearest adjacent reports with a finger of the left hand at the same number of the stationary scale as the number with which the documents to be withdrawn coincide at their right hand edge the reports of one salesman can be withdrawn without disturbing or dislodging the others. When the reports of one salesman have thus been withdrawn the reports of the next salesman are left projecting and capable of being withdrawn in the same manner and so on through all those distributed on the table. As fast as the reports are withdrawn they are laid face up in one pile, the consequence being an alphabetical occurrence of the reports in the pile. To put the matter in a more concrete way and as shown in Fig. 1, if the documents are eight inches wide the reports will aline at their right hand edges at 9 on the number ribbon P and "9" on the permanent scale will indicate the pressing point for holding down the documents at the left. The two scales can be used for chronological arrangement of the several alphabetical groups in the same way except that when distributed according to dates the documents are withdrawn from the left hand side, the numbers of the permanent scale being used as the date placing positions and the numbers of the ribbon P used as the pressing or holding indications. If a series of numbers be placed on the name ribbon as suggested in Fig. 1 said ribbon can be used in connection with the permanent scale for chronological sorting.

Where the documents used in a business are not of different dimensions the two numbered scales can be made or left in permanent relation to each other.

The forms of the parts can be changed without departing from the gist of the invention as claimed.

What I claim is:

1. Means for facilitating the sorting of documents originating from various persons comprising in combination an elongated table for primarily depositing the documents, a rail extending longitudinally of the table carrying the names of such persons, said names being regularly spaced from each other, a regular series of similarly spaced numbers paralleling said names, and a second series of similarly spaced numbers paralleling said named series the numbers thereof being in non-coinciding relation to the first series of numbers whereby documents deposited on said table alining with said names are grouped in distinguishable piles readily separable in substantially the manner described.

2. Means for facilitating the sorting of

documents originating from various persons comprising in combination an elongated table for primarily depositing the documents, a rail extending longitudinally of the table carrying the names of such persons, said names being regularly spaced from each other, a regular series of similarly spaced numbers paralleling said names, and a second movable series of similarly spaced numbers paralleling said named series so that the numbers thereof can be placed in non-coinciding relation to the first series of numbers whereby documents deposited on said table alining with said names are grouped in distinguishable piles readily separable in substantially the manner described.

JAMES H. FULLER.
